DESK APPLIANCE

Frank Riggio, Los Angeles, Calif., assignor to
 Anderson School Equipment Co., Los Angeles,
 Calif., a corporation of California

Application May 12, 1942, Serial No. 442,589

2 Claims. (Cl. 311—17)

This invention relates to means for mounting or supporting typewriters, adding machines, etc., and has more particular reference to means for adapting a conventional desk, table, or the like, to carry or mount a typewriter, adding machine, or similar device. A general object of this invention is to provide a simple, practical and highly effective device applicable to a typical office desk, or the like, and operable to support a typewriter or adding machine in position for convenient use.

Many devices have been developed for supporting typewriters and adding machines on office desks and tables. So far as I am aware all of these prior devices embody metal brackets, metal braces, metal attaching parts, etc., and, in most instances, the prior devices have been heavy and costly and required permanent or semi-permanent attachment to the desk or table.

Another object of this invention is to provide a means for mounting or supporting a typewriter on a typical office desk, table, or like article of furniture that may be constructed entirely of wood. The improved device of the present invention does not involve or require any metal brackets, braces, or other metal parts.

Another object of this invention is to provide a typewriter mounting means of the character mentioned that may be securely and dependably applied to the desk without altering or defacing the desk and without the necessity of utilizing screws, bolts, or other attaching parts liable to deface or injure the desk.

Another object of this invention is to provide a typewriter mounting means that may be readily anchored in a drawer-receiving space of a desk, or the like, following removal of the drawer.

A further object of this invention is to provide a means for mounting or supporting a typewriter or adding machine on a desk, table, or the like, that may be very easily and quickly installed for use and readily removed after use. The installation and removal of the device require only a few seconds and do not necessitate the use of tools.

The various objects and features of my invention will be fully understood from the following detailed description of typical preferred forms and applications of my invention, throughout which description reference is made to the accompanying drawing, in which:

Fig. 1 is a fragmentary perspective view of a conventional desk showing a preferred embodiment of the invention in the operative position thereon. Fig. 2 is an enlarged fragmentary ver-

tical detailed sectional view showing the device in the operative position. Fig. 3 is a fragmentary plan or top view of the device apart from the desk. Fig. 4 is a fragmentary vertical detailed sectional view taken substantially as indicated by line 4—4 on Fig. 2 and Fig. 5 is a side elevation of another form of the invention removed from the desk.

The typewriter mounting means of the present invention is adapted to be applied to previously constructed desks and it is a feature of the invention that the device may be used with conventional desks, tables, etc., without any modification whatever in the original desk or table structure. The use of the device does not necessitate the alteration of any desk parts and upon the removal of the device the desk may be restored to its original or normal condition with its full drawer capacity. It is to be understood that the proportions of the device may be varied to adapt it for use with different makes, styles and kinds of desks and tables and that minor variations may be necessary in the device in certain instances. Accordingly, the invention is not to be construed as limited or restricted to the specific forms and applications of the invention herein described.

The desk illustrated in the drawing is of a type used in offices, schools, residences, etc., and comprises a top 10 and supporting legs 11. The portion of the desk illustrated has a pair of front legs 11 and, in accordance with the usual practice, a tier of drawers 12 is provided between the legs. A center drawer 13 is also provided and is rather shallow to leave ample space for the knees of the user. A pull-out writing board 14 is directly above the drawers 12 and is below the top 10. The fronts of the drawers 12 have suitable pulls 15 and the drawer fronts may normally lie flush with the front of the desk. In accordance with the usual practice the drawers 12 are spaced apart at their fronts by horizontal spacing members 16. The members 16 extend between the legs 11 and are rigid or fixed parts of the desk. An upper member 16 occurs between the pull-out board 14 and the upper drawer 12. The drawers 12 are individually removable from the desk. The construction thus far described is conventional and is typical of office desks, etc.

The typewriter mounting means of the present invention is adapted to be removably anchored or secured in a drawer space following removal of one of the drawers. In most instances, it is desirable to mount the device in the space normally or originally occupied by the upper drawer

12 because this places the device in position for the support of the typewriter at a correct elevation for use by a person seated at the desk.

The improved typewriter mounting means of the invention may be said to comprise, generally, a supporting or mounting board 17 for the typewriter, or the like, means 18 on the board 17 for bearing in and occupying the mouth of the drawer space and means 19 for latching or retaining the device in the drawer space.

The board 17 is provided to carry the typewriter, adding machine, or other machine that is to be used at the desk. The board 17 is a generally rectangular or substantially square member and preferably has substantial thickness to have ample mass and weight to give stability to the device. In practice the board 17 may be formed of the same stock as the desk top 10 and, if desired, may have the same finish as the desk top and other parts of the desk. In accordance with the invention the board 17 is adapted or intended to occupy a horizontal position where it projects forwardly from the front of the desk. In the preferred construction the exposed major portion of the board 17 is broader or wider than the top drawer space. In the case illustrated the board 17 is of substantial width to have two opposite longitudinal edges in the same vertical planes as the outer sides of the spaced legs 11. The board 17 has an inner or rear portion of reduced width which I will term a tongue 20. The tongue 20 is of such width that it may be readily entered in the top drawer space of the desk. Rearwardly facing shoulders 21 occur at the opposite longitudinal edges of the board 17 where the tongue 20 joins the body of the board. These shoulders 21 are engageable with the forward faces of the legs 11 to limit the inward movement of the board. The shoulders 21 formed on the thick board 17 are of extensive area and have ample bearing engagement with the legs 11. The reduced portion or tongue 20 of the board is preferably proportioned so that its opposite edges may cooperate with the inner sides of the legs 11 to further steady the device and to assist in holding it against lateral shifting. As best illustrated in Fig. 2 of the drawing the tongue 20 is adapted to extend a considerable distance into the drawer space. It will be observed that the board 17 is a simple one piece member of wood, or the like.

The means 18 is operable to fit or bear in the drawer space to support or mount the board 17. The means 18 includes a strip member 22 on the upper side of the board 17 and a similar strip member 23 on the under side of the board. The members 22 and 23 are rigidly fixed to the board 17 and extend transversely thereof. The members 22 and 23 are located to engage in the mouth of the drawer space or opening, the members occurring in a common vertical plane where the tongue 20 joins the body of the board 17. This is best illustrated in Fig. 3 of the drawing where it will be seen that the forward faces of the members 22 and 23 are in the same vertical plane as the shoulders 21. Accordingly, when the shoulders 21 are engaged against the forward faces of the desk legs 11 the members 22 and 23 have their forward faces flush with the face of the desk.

The length of the members 22 and 23 is preferably substantially equal to the width of the tongue 20 so that the opposite ends of the members are engageable with the side walls of the drawer opening to assist in steadyng the de-

vice and to hold the device against horizontal or lateral movement. The members 22 and 23 are preferably proportioned to completely occupy those parts of the drawer opening above and below the board 17. In other words, the lower edge of the member 23 is adapted to rest on the desk member 16, which defines the lower wall of the drawer receiving opening and the upper edge of the member 22 may cooperate with the lower side of the member 16 which defines the upper wall of the drawer opening. The lower rear corner of the member 23 is bevelled off or rounded away as at 24 to facilitate the insertion and removal of the board 17, as will be later described. It will be seen that the engagement of the members 22 and 23 in the drawer opening holds the board 17 against lateral movement in both directions and holds the board against bodily downward movement and against bodily upward movement. Further, the members 22 and 23 occupy or close the mouth of the drawer space to give the desk and desk attachment a finished appearance.

The means 19 serves to removably latch the board 17 in the operative position on the desk and to dependably support the board against downward tilting or swinging. The means 19 includes one or more latch blocks 25 for cooperating with the inner side of the uppermost member 16 to securely hold the board 17 against downward swinging. In the preferred construction illustrated there are two latch blocks 25 fixed on the upper side of the tongue 20 and spaced apart to run along the longitudinal edges 35 of the tongue. The latch blocks 25 may extend rearwardly from the member 22 to the rear end of the tongue. The blocks 25 may be simple members of wood. As clearly illustrated in Figs. 2 and 5 of the drawing, the latch blocks 25 are 40 of greater height than the member 22 to project upwardly beyond the member so that their forward ends 26 constitute forwardly facing shoulders 26 for cooperating with the rear face of the uppermost member 16. The cooperation 45 of the shoulders 26 with the rear side of the member 16 positively holds the board 17 against bodily forward movement and prevents downward tipping or swinging of the board 17 under the weight of the typewriter or other object 50 placed on the board. The upper edges of the blocks 25 preferably remain clear of the pull-out writing board 14 but, in some cases, it may be desired to proportion the blocks 25 so that their upper edges may bear on the writing board 14. 55 The upper outer corners or edges 27 of the blocks 25 may be grooved out to remain clear of the corner brace elements and drawer guides 28 of the desk.

The latch means 19 may further include a 60 latch 29 on the member 22 for cooperating with the forward face of the uppermost member 16 to hold the board 17 against the upward swinging movement required as a preliminary to withdrawal or removal of the device. The latch 29 may be a simple elongate part pivotally secured on the forward face of the member 22 by a pivot pin 30. The latch 29 is movable between a substantially horizontal position where it is clear of the drawer defining member 16 and a substantially vertical position, such as illustrated in Figs. 1 and 2 of the drawing, where it cooperates with the member 16 to hold the board 17 against upward swinging and inward movement. The latch 29 is not required in every application 75 of the invention and is an optional element.

It is to be understood that where the device is to be used in a table drawer space the parts may be proportioned to fit the table drawer space which is usually shallower than a typical desk drawer space.

Fig. 5 of the drawing illustrates an embodiment of the invention having an apron 31 on the board 17. The apron 31 may depend from the outer edge of the board 17, that is, from the edge of the board that is most remote from the knee hole of the desk. The apron 31 may be proportioned so that its lower edge is a substantial distance above the floor and so that its inner edge engages or is immediately adjacent the front face of the desk. It is preferred to either hingedly or removably secure the apron to the base or board. In the case illustrated hinges 32 secure the apron 31 to the board 17 so that it may be folded against the board for storage purposes, etc.

It is believed that the utility and practicability of the typewriter mounting means will be readily understood from the foregoing detailed description. Preparatory to using or installing the device the selected drawer is removed from the desk. In this connection it should be observed that the device may be mounted at either side of a desk having two spaced tiers of drawers. It is usually preferable to remove the uppermost drawer of the selected tier. With the drawer removed the tongue 20 is entered in the drawer space and the board 17 is manipulated or, tipped up and then swung down, to engage the latch blocks 25 behind the uppermost member 16. This brings the shoulders 26 against the member 16 and positions the members 22 and 23 in the mouth of the drawer space so that the lower edge of the member 23 rests on the member 16 which defines the lower wall of the drawer space. Where the device embodies the latch 29 the latch may then be pivoted to cooperate with the forward face of the uppermost member 16. The device is then in condition for use. A typewriter, adding machine, or the like, may be placed on or secured to the horizontal board 17 projecting from the face of the desk.

When it is desired to remove the board 17 the latch 29 is swung free of the uppermost desk member 16. The board 17 is then swung upwardly from its outer end and its inner part is moved downwardly to disengage the shoulders 26 from the uppermost member 16 of the desk. With the latch blocks 25 disengaged from the uppermost member 16 the board may be readily withdrawn from the desk. The rounded cor-

ner 24 of the member 23 facilitates the mounting and removal of the device.

It will be observed that the entire device of the invention may be constructed of wood, or the like. The board 17, the members 22 and 23 and the latch blocks 25 are all of such nature that they may be constructed of wood.

Having described typical preferred forms and applications of my invention, I do not wish to be limited or restricted to the specific details herein set forth, but wish to reserve to myself any variations or modifications that may appear to those skilled in the art or fall within the scope of the following claims.

15 Having described my invention, I claim:

1. A device for use on a desk having a drawer-receiving opening with a member extending across the top of the entrance to the opening, the device including a supporting board having 20 a tongue of reduced width adapted to be introduced into the entrance of said opening, a transversely disposed strip on the upper side of the tongue adapted to engage in the entrance of said opening and bear upwardly against the under side of said member, a transversely disposed strip on the under side of the tongue adapted to engage in the entrance of said opening and rest against the lower wall of said entrance, and blocks on the upper side of the tongue extending 25 rearwardly from the first named strip, the forward ends of the blocks being adapted to latch with the rear side of said member to releasably hold the board in the supporting position.

2. A device for use on a desk having a space 30 for receiving a drawer or the like with a member extending across the top of the entrance to the space, the device including a supporting board having a tongue of reduced width adapted to be introduced into the entrance of said space, a transversely disposed strip on the upper side of the tongue adapted to engage in the entrance of said space and bear upwardly against the under side of said member, a transversely disposed

45 strip on the under side of the tongue adapted to engage in the entrance of said space and rest against the lower wall of said entrance the tongue and said strips completely occupying said entrance of the space, one or more latch blocks 50 on the upper side of the tongue for cooperating with the rear side of said member to latch the board in supporting position, and a latch on the first named strip for cooperating with the forward side of said member to prevent upward 55 swinging of the board.

FRANK RIGGIO.
